CUTTING MACHINE

Bela B. Junkunc, Chicago, Ill., assignor to Bela B. Junkunc, Alexander Junkunc, Sr., Alexander Junkunc, Jr., and Joseph G. Junkunc, a partnership doing business as J. & J. Tool & Machine Co., Chicago, Ill.

Application April 1, 1948, Serial No. 18,456

4 Claims. (Cl. 164—44)

1

This invention relates to a cutting machine particularly adapted to cut elongated metal facia board strips transversely, to the desired length.

Facia boards for use in connection with Venetian blinds are fabricated in long lengths and are then painted by the manufacturer. The painting is usually done at the factory because most jobbers or installers of Venetian blinds have small shops and are not equipped to do the paint job in a commercially feasible manner. The installer buys the facia boards in long lengths and then cuts them into shorter lengths necessary to fill particular orders. This system of distribution has been found to be most suitable for the industry. It eliminates the need for the installer to carry a large stock and has many other advantages. It has heretofore had the disadvantage, however, that very often the installer, when cutting facia boards to required lengths, deforms the cut ends. These deformed ends must be straightened, and if the paint has chipped off because of the deformation, the installer must retouch the paint along the exposed surface adjacent the cut end. The time and expense involved in doing this has been substantial and has added to the cost of the Venetian blinds to the consumer.

The machine of the present invention cuts flanged metal strips such as facia boards, without deformation. It comprises a die over which the facia board is positioned and a knife mounted and shaped so as to cut inwardly from each edge of the facia board as hereinafter described, and thereby cut it without any distortion or deformation. The elimination of the deformation heretofore incidental to cutting facia boards also eliminates the cause of paint chipping and the need for paint retouching.

Although the cutting machine of the present invention is designed primarily for cutting metal facia boards, the same principles may be utilized for cutting any metal strips, particularly those having spaced flanges at either or both edges.

The structure by which the above advantages are attained will be described in the following specification, taken in conjunction with the accompanying drawings, in which:

Figure 1 is a side elevation of a cutting machine embodying the invention, with the facia board to be cut positioned on the die just prior to the start of the cutting operation;

Fig. 2 is an end elevation of the cutting machine shown in Fig. 1;

Fig. 3 is a cross sectional view, taken along the line 3—3 of Fig. 1;

2

Fig. 4 is a cross sectional view, taken along the line 4—4 of Fig. 1;

Fig. 5 is a top plan view of the die shaped to fit a strip of facia board;

5 Fig. 6 is a detail perspective view of one form of a strip of facia board for the cutting of which the machine is designed;

Fig. 7 is a fragmentary sectional view taken along one side of the knife, showing the positions 10 of the parts after the first edge of the facia board has been severed and at the start of the cutting operation on the second edge; and

Fig. 8 is a side elevation, similar to Fig. 1, showing another embodiment of the invention.

15 In the drawings, the reference numeral 2 indicates a base having a pair of frame members 3 and 4 secured thereto in any suitable manner. Frame members 3 and 4 are duplicates of each other. Member 3 comprises a front leg 5, a rear leg 6, and an intermediate portion 7 spaced above base 2 and connecting the upper portions of legs 5 and 6. Preferably legs 5 and 6 and connecting portion 7 are integral, but this is not essential. Frame member 4 is provided with corresponding legs 8 and 9 connected by intermediate portion 10. The lower surfaces of intermediate portions 7 and 10 are spaced far enough above base 2 to provide a space for a die 11 secured to base 2 between legs 5, 8 and 6, 9.

30 Die 11 is made in two duplicate parts, spaced apart a distance sufficient to receive a knife 12 therebetween. Frame members 3 and 4 have their adjacent edges also spaced apart a distance slightly greater than the thickness of knife 12.

35 Knife 12 is pivotally secured at one end between legs 5 and 8 by a stud 13 which fits in registering apertures in legs 5 and 8.

The top surface of die 11 is fluted, as indicated at 14, to conform to the contour of the 40 fluted surface of facia board 15. In general, the top surface of the die conforms to the contour of the top surface of the facia board. These may be flat or may have any other desired shape, as the ornamental fluted shape illustrated.

45 The upper portion of die 11 is recessed at each edge, as shown at 16 and 17, to receive the flanges 18 and 19 which are bent downwardly and inwardly from the edges of facia board 15. The depth of the top portion of die 11 is slightly less than the width of facia board 15 to facilitate positioning of the facia board on die 11. This difference between the depth of the die and the width of the facia board causes the facia board to overlap one edge of the die, as indicated at 20, Fig.

55 1. The importance of this overlap will appear in

connection with the discussion of the operation of the cutting machine.

An ear 21 projects upwardly from frame member 3 adjacent rear leg 6. A similar ear 22 projects upwardly from frame member 4. A handle 23 has bifurcated ends 24 and 25 which straddle knife 12. Ends 24 and 25 are pivotally secured to ears 21 and 22, respectively. A screw 26 passing through an aperture in ear 21 and threaded into end 24 serves as a pivot for end 24, and a similar screw 27, passing through an aperture in ear 22 and threaded into end 25, serves as a pivot for end 25.

Knife 12 is provided with an arcuate cam slot 28. A roller 29 extending through apertures in ends 24 and 25 passes through cam slot 28. Washers 30 and 31 are positioned on the ends of roller 29 adjacent the outer surfaces of ends 24 and 25, respectively. Cotter pins 32 and 33 are secured to opposite ends of roller 29 adjacent the outer surfaces of washers 30 and 31. These cotter pins hold roller 29 in position and permit it to roll along the edge of cam slot 28. This cam slot and roller connection between knife 12 and handle 23 controls the path of travel of the knife as the handle is moved in a manner hereinafter described.

The shape of knife 12, as shown in Fig. 1, resembles a crescent having rounded ends. The inside edge 34, which constitutes the cutting edge, is of irregular contour. The front portion of cutting edge 34, nearest to pivot 13, is recessed to a greater extent than the rear portion so that the rear portion is closer to the top of die 11 when knife 12 is in position to start the cutting operation. An intermediate portion of the cutting edge, preferably a portion relatively closer to the front portion than the rear portion, is recessed to even a greater extent than the front portion, as shown, although this is not essential. In fact, it may be recessed to a lesser extent. In addition to the irregular contour, cutting edge 34 is preferably serrated to make it conform to the fluted surface of facia board 15 as successive portions of it come into contact with the top surface of the facia board.

Referring to Fig. 1, when handle 23 is moved in the direction indicated by arrow A, knife 12 is moved around stud 13 in a clockwise direction, as indicated by arrow B in Fig. 1, because roller 29, which pivots handle 23 to ears 21 and 22, is engaged in cam slot 28. As the rear portion of knife 12 is forced downwardly it engages the rear edge of facia board 15 adjacent flange 19 and pushes it against the rear edge of die 11 before it starts cutting through this edge of the facia board. This pressure, towards the left side as viewed in Fig. 1, insures a solid backing for the edge of the facia board during the cutting operation so that when the knife enters space 35 between the two parts of die 11 it will not distort or deform the edge of the facia board being cut.

When knife 12 has cut through about half or a little more than half the width of facia board 15, the forward portion of cutting edge 34 engages the edge adjacent flange 18 before the adjacent portion of cutting edge 34 engages the top surface of the facia board. Continued movement of handle 23 causes the forward portion of cutting edge 34 to push facia board 15 rearwardly until its forward edge is firmly positioned against the forward edge of die 11. The overlap 20 of facia board 15 relative to die 11 permits this shifting. The forward portion of cutting edge 34

then cuts through the forward edge of facia board 15 in the same manner that the rear portion cuts through the rear edge of the facia board. After the forward edge of facia board 15 is cut through, cutting edge 34 completes the severance of the facia board by cutting downwardly through the portion of the top of facia board 15 adjacent its forward edge. The cutting of this final portion of the facia board is from opposite directions, made possible by the shape of the cutting edge. The shifting of facia board 15 on die 11 as described prevents deformation of either edge during the cutting operation.

In the embodiment shown in Fig. 8, knife 36 is pivoted between legs 37 at one end of the machine, as indicated at 38. Handle 39 is fixed to knife 36 adjacent the pivoted end. The irregular contour of cutting edge 40 is similar to cutting edge 34, with the portion closest to pivot 38 spaced farther from the top of die 11 than the portion at the opposite end of the knife. As handle 39 is pulled to the left, as viewed in Fig. 8, end 41 pushes facia board 15 to the right against the edge of die 11 before it starts cutting. As in the case of the other embodiment, the portion of cutting edge 40 nearest pivot 38 pushes facia board 15 back in the opposite direction before the cutting operation is completed, and then cuts its adjacent edge so that neither edge of the facia board is deformed during the cutting operation.

Although I have described two preferred embodiments of my invention in considerable detail, it will be understood that the description thereof is intended to be illustrative, rather than restrictive, as many details may be modified or changed without departing from the spirit or scope of the invention. Accordingly, I do not desire to be restricted to the exact details, except as limited by the appended claims.

40 I claim:

1. In a cutting machine, a base, a frame comprising two upstanding members spaced apart on said base, a die secured to said base under said frame, said die comprising two parts separated to permit entry of a knife therebetween, a knife pivoted at one end between said frame members adjacent one end of said frame, said knife having an irregularly curved cutting edge, and a cam slot above said cutting edge, a handle having bifurcated ends straddling said knife and pivoted to said frame adjacent the end opposite that to which said knife is pivoted, and a roller secured to said bifurcated ends, said roller passing through said cam slot.

2. In a cutting machine, a base, a frame comprising two upstanding members spaced apart on said base, a die secured to said base under said frame, said die comprising two parts separated to permit entry of a knife therebetween, a knife pivoted at one end between said frame members adjacent one end of said frame, said knife having an irregularly curved cutting edge and a cam slot above said cutting edge, a handle pivoted to said frame adjacent the end opposite that to which said knife is pivoted, and a member projecting from said handle through said cam slot.

3. The cutting machine of claim 2 wherein said knife is pivotally mounted for rotation about only a single axis, said irregularly curved edge of said knife being recessed to a greater extent at one end than the other end thereof, and the intermediate portion of said cutting edge being recessed to a greater extent than either end thereof, to provide a cutting edge

which is adapted, when pivoted toward said die about said axis, to progressively enter the space between said die parts starting first from one end of said cutting edge and progressing toward the center thereof, and then from the other end of said cutting edge progressing toward the center thereof.

4. The cutting machine of claim 2 wherein said die is provided with longitudinally extending recesses to receive the flanges of a flanged metal strip to be cut, the width of said die being slightly less than the width of the flanged metal strip which is to be cut, said irregularly shaped cutting edge, when pivoted toward said die, being adapted to progressively enter the space between said die parts starting from one end thereof and progressing toward the center portion of said cutting edge and then from the

other end thereof progressing toward the center portion of said cutting edge whereby flanged metal may be cut without deformation thereof.
